UNITED STATES PATENT OFFICE.

RICHARD L. LLOYD, OF CANANEA, MEXICO.

APPARATUS FOR CONVERTING METALS.

No. 851,817.

Specification of Letters Patent.

Patented April 30, 1907.

Application filed August 4, 1906. Serial No. 329,137.

To all whom it may concern:

Be it known that I, RICHARD L. LLOYD, a citizen of the United States, now a resident of Cananea, Sonora, in the Republic of Mexico, have invented certain new and useful Improvements in Apparatus for Converting Metals, of which the following is a specification.

My present invention relates to the refining of metals, and especially to the refining of copper, in which it finds its greatest utility. It has to do with that part of the process in which copper matte is converted to metallic copper in an apparatus commonly known as a "converter," and it consists in new combinations of converters with other apparatus by which the process may be rendered continuous, so that the copper matte may be delivered direct from the furnace in which it is made, and with suitable flux carried through the apparatus herein described continuously, coming out at the end of the process as metallic copper. So far as I am aware no continuous operation of converting apparatus in the sense here employed has heretofore been possible.

In brief, the apparatus illustrated consists of feeding barrels somewhat resembling converters in their construction, a primary and a secondary converter, all of the horizontal type, and all so arranged that the materials under treatment may pass consecutively from one part of the apparatus to another by gravity; suitable arrangements are made for the removal of the slag as it forms, and for the further refining of the copper, if desired, after it leaves the secondary converter.

Another important feature of the apparatus is that the blast, after passing through the first converter, (where it becomes intensely heated by the oxidation of the materials and their combination into the slag, and especially by the oxidation of the sulfur and iron), instead of passing directly into the atmosphere, passes through the feeding barrels, as I prefer to call them, and thence to the stack through the secondary converter, in its course passing over the exit hearth of the secondary converter, into which the metallic copper is discharged at the completion of the operation, and which is the coolest point in the process. This arrangement prevents the chilling of the copper and also tends to keep the second converter highly heated, the reactions in that

part of the operation not being so intense as in the first and therefore not producing so much heat.

The process by which the matte is refined and to effect which I have devised the present invention is not claimed in this application, being covered by my pending application, Serial No. 329,136 filed August 4th, 1906. Obviously I am not restricted in the use of the present apparatus to the particular process set out in that case, although I believe that to be one of great utility, but aim to cover in this case all of the utilities inherent in the apparatus.

The accompanying drawings show an embodiment of the mechanical features of my invention.

In these, Figure 1 is a plan of the arrangement of converters and feeding barrels. Figs. 2 to 5 are elevations from different sides of the apparatus shown in Fig. 1. Figs. 6—6^a are respectively an end elevation and a partial section of the primary converter D. Figs. 7—7^a are respectively an end elevation and partial section of the secondary converter F. Figs. 8—8^a are an elevation and a section upon the line 8—8 of one of the feeding barrels, which are substantially alike in construction.

Referring now to Figs. 1 to 5, D is the primary converter, composed, as is usual, of a metallic shell with a suitable refractory lining. In the apparatus which I employ when used in the particular process described in my pending application already referred to, the linings of all the converters and feeding barrels may be basic or neutral, since I furnish the necessary silicious flux in other ways and do not employ the common tamped silica lining; I prefer for the lining a magnesite or similar brick, which is not only refractory but does not break down under the reactions inherent in the process. The end of the converter nearest the hearth C, to be presently described, presents no peculiarity, being only slightly contracted, but the end next the hearth E (see Figs. 6 and 6^a) is partly closed by a dam d, the shape of which is such that it will retain the copper sulfid to a certain depth in the bottom of the converter, while the slag, when enough is formed, will flow over into the hearth E. The converter may be rotated by means of its motor Q¹ (see Fig. 1), until the dam d is turned to one side,

whereupon it discharges completely into the hearth E. The twyers O, seen best in Fig. 2, are supplied with air through a flexible pipe M leading from the source of air pressure, so that the pressure may be kept on until the twyers are lifted by the rotation of the converter above the molten material, keeping them clear.

The two feeding barrels A—A¹ are of substantially the same construction, seen best in Figs. 8—8^a; they consist, like the converter, of metallic shells lined with appropriate basic or other refractory linings. At the ends nearest the hearth C are openings A² into which, through the openings C¹—C² in the hearth, may be charged the molten matte and slag or other flux by any suitable means. By the motors Q Q, the feeding barrels may then be rotated as desired and the melted material, maintained at very high temperature by the blast from the converter D passing across the hearth and through the barrels, may thus be discharged upon the hearth from the openings A² as they are lowered in such proportions as the engineer desires, and will then enter the converter (being practically at combination temperature) through the spout C³; the openings A³ permit the blast to proceed through the barrels.

The construction of the hearth C will be obvious from the drawings and embraces no peculiarity. A furnace B is provided so that when it is desired to start the operation, or when under some conditions it is desired to use a dry flux or otherwise, fire may be provided; and an opening L is also provided as an outlet if the slag should foam over, or any other accident occur.

The construction of the hearth E is best understood from Figs. 1, 2, and 4; it is closed on the side toward the stack, not illustrated, by a wall E¹, having perforations at the bottom of it, and an abutment E³ beyond the wall and higher than the perforations constitutes with the wall a siphon dam through which the copper sulfid formed in the converter D may pass, but which is impervious to the slag; the latter is removed from time to time, or may flow continuously from the opening E² (see Fig. 4); after passing over the abutment E³ the copper sulfid flows through the spout F² into the secondary converter F. Passing into the converter F the copper sulfid is again "blown" to metallic copper, the sulfur being oxidized into sulfurous acid gas; as already pointed out this part of the process does not generate so much heat as that which is carried on in the converter D. The blast from the converter F passes by the flues H, J, to the stack, which is not illustrated. In the delivery end of the converter F (see Figs. 7—7^a), is a siphon dam somewhat like that in the hearth E, consisting of the wall f with perforations f¹ and an abutment f² located beyond it; the metallic cop-

per, which is heavier than copper sulfid or oxid, passes through the perforations and over the abutment into the hearth G (see Figs. 1 and 5); here it may be poled or otherwise further refined as may be desired, and may be removed by the opening g. The blast from the converter D, as already indicated, after passing through the barrels A—A¹ enters the flue N and then passes across hearth G to the converter F, and thence to the stack. Of course, the remaining heat may be utilized in any desired way, as by heating boilers or the like, or acid chambers may be formed in the flues for the more economical practice of the process, but these particulars having no relation to my invention except that they are not inconsistent with its use, are not illustrated or described.

Having thus described my invention, what I claim and wish to protect by Letters Patent of the United States is:—

1. In an apparatus for refining metals, the combination of a horizontal converter revolvable about a horizontal axis, with separate independently controllable feeding apparatus for the flux and for the metal to be refined located between the converter and the stack, and so arranged that the blast from the converter passes through the feeding apparatus.

2. In an apparatus for the refining of metals, a feeding device consisting of a barrel, having an opening in one end adjacent to the side, with means for revolving the barrel; whereby when the opening is brought to the top of the revolution, material to be treated may be charged thereinto, and by revolving the barrel to bring the opening below, may be discharged therefrom at desired times and in desired amounts.

3. In an apparatus for refining metals, feeding apparatus for the flux and the metal to be refined, consisting of feeding-barrels, each having an opening in one end adjacent to the side thereof, with means for independently revolving them so that the discharge of the flux and of metal may be independently controlled.

4. In an apparatus for refining metals, the combination with primary and secondary horizontal converters revolvable about horizontal axes, of separate feeding-barrels for the flux and the metal to be refined, located between one end of the primary converter and the exit hearth of the secondary converter, and so arranged that the blast from the primary converter passes through both of the feeding barrels and through the secondary converter to the stack; with a connection between the other ends of the two converters, impervious to the blast and to the slag, but permitting the flow of the partially refined matte.

5. In an apparatus for refining metals, a converter series comprising communicating primary and secondary converters, means

- for feeding the charge into the primary converter and means for conducting the blast from the primary converter to the charge, to control the temperature of the charge.
5. In an apparatus for refining metals, a converter series comprising communicating primary and secondary converters, means for feeding the charge into the primary converter, means for conducting the blast from the primary converter to the charge for controlling the temperature thereof, and means for finally conducting the blast to the secondary converter.
6. An apparatus for converting metals, comprising a plurality of horizontal converters and a feeding apparatus, the first converter being lower than the feeding apparatus, and means for discharging the partially refined matte into a second converter, lower than the first.
7. An apparatus for converting metals, comprising a plurality of horizontal converters and feeding apparatus located between adjacent ends of the converters; the primary converter being lower than the feeding apparatus so that the materials to be treated may flow thereinto by gravity, and the secondary converter being lower than the primary; with a connection between the converters at one end, through which the partially refined material may flow, the said connection being impervious to the blast and to the slag; and a passage for the blast from the first converter through the feeding apparatus and the second converter to the stack.
8. An apparatus for converting metals, comprising a plurality of horizontal converters and feeding apparatus located between adjacent ends of the converters; the primary converter being lower than the feeding apparatus so that the materials to be treated may flow thereinto by gravity, and the secondary converter being lower than the primary; with a connection between the converters at one end, through which the partially refined material may flow, the said connection being impervious to the blast and to the slag; and a passage for the blast from the first converter through the feeding apparatus and the second converter to the stack.
9. The combination, with a converter, of separate feeding barrels for the metal to be treated and for its flux, means for charging the materials into the feeding barrels in one position, and means for rotating the feeding barrels and thereby releasing the charge into the converter.
10. An apparatus for the refining of metal, consisting of a plurality of converters and a feeding apparatus so arranged between them that the blast from the first converter passes through the feeding apparatus into the second converter.
11. In an apparatus for refining metals, the combination of a converter, feeding apparatus for the metal to be refined, feeding apparatus for the flux, an opening for the blast from the first converter to the feeding apparatus, means for passing the metal from the first converter into the second, and an opening for the blast from the feeding apparatus into the second converter; whereby the metal passes in one direction from the feeding apparatus through the two converters to an outlet, and the blast passes from the first converter through the feeding apparatus and the second converter to a stack, in the opposite direction to the metal.
12. The combination of a series of converters for the successive refining of metal,
13. The combination of a plurality of converters part of which receives relatively impure metal containing a considerable amount of oxidizable impurities, whereby it is maintained at a relatively high temperature; and the remainder of which receive the metal after it has been partially purified, so that the oxidation of the impurities therein is less than in the first part, whereby the heat therein is relatively less; with means for passing the blast from the first part through the second and across the exit for the metal therefrom; whereby the surplus heat from the first part of the converter is used to prevent the chilling of the metal in the second.
14. The combination, with two converters for the successive refining of metal, of feeding devices for the first converter connected between one end thereof and the exit hearth of the second converter, a dam between the other end of the first converter and the stack, permitting the flow of metal into the second converter and stopping the blast from the first from passing into the stack, and a channel for the blast through the feeding devices and across the exit hearth of the second converter; whereby the metal from the first converter after being partially refined passes into the second converter for further treatment, and the blast from the first converter passes through the feeding devices and the second converter to the stack.
15. A conversion apparatus for metal refining, comprising a pair of substantially horizontal converters revoluble about longitudinal axes, with a horizontal feeding apparatus located between them.
16. In a conversion apparatus for metal refining, a pair of horizontal converters revoluble about longitudinal axes, a connection between the two converters at one end through which metal may pass but sealed against the blast, a horizontal feeding apparatus located between the other ends of the converters, and a passage for the blast from the first converter through the feeding apparatus and the second converter.
17. The combination of a pair of converters for the successive refining of metal, with a passage for the metal from one to the other, said passage being impervious to the blast; with another connection, open to the blast, between the converters.
18. The combination of a pair of approximately horizontal converters for the successive refining of metal, with a passage for the metal from one to the other, said passage be-

ing impervious to the blast; with another connection, open to the blast, between the converters.

19. The combination of a pair of approximately horizontal converters revoluble about longitudinal axes, with means for rotating them as desired, a passage for the metal from one converter to the other at adjacent ends, the passage being impervious to the blast; 10 with a connection, open to the blast, between the converters at their other ends.

20. In an apparatus for refining metals, the combination with converters and feeding apparatus therefor so located that the blast 15 from the converter passes therethrough to the stack, of an auxiliary furnace arranged to heat the contents of the feeding apparatus at desired times.

21. In an apparatus for refining metals, a suitable converter, means for feeding thereto at desired times from independent sources suitable proportions of the crude metal and a flux respectively, and means for directing the blast of the converter upon the 25 materials delivered thereto, during the feeding operation.

22. In an apparatus for refining metals, a suitable converter, means for introducing thereto from independent sources suitable proportions of the metal to be refined and a flux therefor, and means for heating the charges of metal and flux so introduced by the blast from the converter.

23. In an apparatus for refining metals, a

suitable converter, means for introducing 35 thereto from independent sources an initial charge of crude metal and a flux therefor, means for removing the partially refined metal from the converter, and means for introducing fresh charges of crude metal into 40 the slag remaining in the converter.

24. In combination with a series of converters adapted to discharge into one another, means for feeding into the first converter of the series suitable proportions of 45 the metal to be refined, and a flux, from independent sources of supply, means for conducting the blast from the first converter through such feeding means and in the path of the discharge contents of the last converter of the series.

25. In combination with a series of converters adapted to discharge into one another, means for feeding into the first converter suitable proportions of the crude 55 metal and a flux from independent sources of supply, means for conducting the blast from the first converter through such feeding means and in the path of and in the opposite direction to the flow of the contents of the last converter.

In witness whereof I have hereunto set my hand this 26th day of July 1906, in the presence of two witnesses.

RICHARD L. LLOYD.
